INVENTOR

Caesar R. Bannihr

UNITED STATES PATENT OFFICE.

CÆSAR R. BANNIHR, OF WEST CHESHIRE, CONNECTICUT.

VELOCIPED-E-HANDLE-BAR FASTENING.

SPECIFICATION forming part of Letters Patent No. 363,354, dated May 24, 1887.

Application filed July 2, 1886. Serial No. 206,916. (No model.)

To all whom it may concern:

Be it known that I, CÆSAR R. BANNIHR, a citizen of the United States, residing at West Cheshire, in the county of New Haven and State 5 of Connecticut, have invented a new and useful Securing Device for Velocipede Handle-Bars; and I do hereby declare that the following is a full, clear, and exact description thereof, reference being had to the accompanying drawings, making a part of this specification.

My invention relates to improvements in velocipede handle-bars of the kind which pass through, or being connected on each side of the 15 steering-head of a velocipede, either by means of a screw and nut, or by being keyed in, or without either the handle-bar being put in on a straight fit, or by passing through a hole in the steering-head of a velocipede.

20 The object of my invention is to secure the handle-bars of a velocipede steering-head without using any of the above-described means, or in case where these means have been applied, but where by accident or otherwise the handle-bar has been broken off. I attain this 25 object by the device illustrated in the accompanying drawings, in which—

Figure 1 is a front view of a steering-head and handle-bars of a velocipede, showing the 30 improvement as applied. Fig. 2 is a cross-section of the invention as applied to the handle-bar.

Similar letters refer to similar parts throughout the drawings.

The steering-head A and handle-bars B constitute the parts of a velocipede to which the improvement is to be applied, which consists of a yoke, C, with a clamp on each end, D, by which means it is secured to the handle-bars. This clamp can be supplied with a screw, 35 cam-lever, wedge, or key; but I prefer to use a screw, as shown at a, which, together with the gibs c, conformed to the handle-bar, and the projecting claw b, reaching around the gibs c and handle-bar B, form the clamp, 40 which need not necessarily be of the same piece as the yoke C, as shown in the drawings, but may be screwed on in whatever direction the handle to which it is to be applied 45 will require.

The yoke C may be of any desired shape to fit the different make of steering-heads and handle-bars.

What I claim as new, and desire to secure by Letters Patent, is—

In a velocipede having handle bar or bars connected with the steering-head, the yoke C, reaching across the steering-head and having a clamp at each end, thus securely connecting the handle bar or bars to the steering-head and 50 to each other in case of a two-part bar, whether by original intention or as a means of repair, substantially as herein set forth and described.

CÆSAR R. BANNIHR.
